[57] CLAIM

The ornamental design for a beverage holder or the like, as shown and described.

DESCRIPTION

FIG. 1 is a perspective view of the beverage holder or the like showing my new design;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a top plan view thereof; and

FIG. 7 is a bottom plan view thereof.

The phantom lines showing a windshield and beverage container in FIG. 1 and beverage containers in FIGS. 2-5 form no part of the claimed new ornamental design.

FIG. 1

FIG. 2

FIG. 3

FIG. 4

FIG. 5

FIG. 6

FIG. 7
